Original application July 11, 1950, Serial No. 173,083. Divided and this application February 26, 1953, Serial No. 339,071

2 Claims. (Cl. 153—67)

The present invention relates to a tube bending machine and method. More particularly, this invention deals with a machine and method for winding elongated tubing stock into an irregular helical form which is subsequently opened up from its helical form to a sinuous tube length adapted for employment in heat exchangers or the like.

In the prior art the formation of sinuous tube lengths for condensers or the like has been accomplished by bending a straight length of tubing about spaced and aligned gages and mandrels, the work being carried by a horizontal table surface, and oscillated or rotated about a plurality of centers with each bend changing its direction from its former bend by alternating from right to left to produce a serpentine sinuous path in a single plane. Such machines are large, complex, and expensive in manufacture and use and limited to the number of coils and the length of coil between bends. This is true in all commercial production machines since it is necessary to sweep the entire preformed portion of the coil around the mandrel from right to left each time another 180° bend is made.

The present invention now provides a simple form of winding apparatus which is employed to spirally wind an elongated length of tubing about forming means defining a rotatable winding frame. The helical tubing coil thus obtained is in the form of an irregular, preferably triangular helix, each bend of which provides for joining these reaches to one another and to adjacent reaches of the sinuous coil.

More particularly, the rotatable winding frame preferably includes a winder plate disposed for rotation on a shaft and having a plurality of spaced winding mandrels projecting therebeyond in planes parallel to the axis of rotation of the plate. Means are provided for training an elongated flexible length of tubing about the mandrels as the plate is rotated about its axis, the tube training or feeding means preferably being screw fed or otherwise advanced along the axis of rotation of the plate to spirally feed the tubing to the winding mechanism to thus form the helical tubing coil. The feeding means successively contacts the winding mandrels as the winding plate is rotated, thereby bending or otherwise deforming the tube about each mandrel in succession. In this manner, the feeding means advances the tubing along the mandrels in a spiral configuration while at the same time forming smoothly curved tubing bends about each mandrel in turn.

Mandrels are also provided for expanding the winder frame or the mandrels when the winding operation has been completed to insure the formation of a smooth, geometrical helical coil, and means are also provided for contracting the winder frame after the coil has been formed and expanded to facilitate removal of the same from the winding apparatus.

The method of the present invention thus contemplates the formation of a tubing coil having an irregular helical configuration, the expansion of the coil after formation to insure the proper helical formation thereof, and the

2

contracting of the coil forming means to facilitate removal of the coil. Of course, the method of the present invention also includes the steps of feeding an elongated tubing length to a winding frame, advancing the tubing lengths across the face of the frame to obtain a spirally wound coil and the maintenance of the winding pressure on the tubing length as it is wound to obtain a uniform coil.

It is, therefore, an important object of the present invention to provide an improved machine for the formation of a helically wound tubing coil adapted for expansion into a sinuous tubing length.

Another important object of the present invention is to provide an improved method of forming a sinuous tube length by the winding of the tube into an irregular helix followed by expansion of the helix to a sinuous configuration.

An additional important object of the present invention is to provide means for producing a sinuous tube whose overall length between ends and the total number of bends are not limited.

It is a further important object of the present invention to provide an improved tube bending machine including a winding frame rotatable about an axis, means for feeding a length of tubing to the frame for forming an irregular helical tubing coil thereabout, and means for expanding the tubing coil after winding is completed to insure the formation of a smooth, regular coil.

Still another important object of the present invention is to provide a tube bending machine including a rotatable winder plate carrying a plurality of spaced mandrels, means for feeding a tubing length about the mandrels as the plate is rotated, and means for advancing the tubing along the axis of rotation of the plate to form a helical coil of the tubing about the mandrels.

Yet a further important object of the present invention is to provide a method of making a sinuous tubing length by feeding an elongated length of tubing about a plurality of spaced mandrels, advancing the tubing along the axial length of the mandrels to form a helical coil thereon and subsequently opening up the helical coil into a sinuous tubing length.

Other and further important objects of the present invention will be apparent from the disclosures in the specification and the accompanying drawings.

On the drawings:

Figure 1 is a broken plan view of an apparatus of the present invention;

Figure 2 is a front elevational view of the apparatus of Figure 1;

Figure 3 is an enlarged fragmentary sectional view taken along the plane III—III of Figure 1;

Figure 4 is an enlarged fragmentary plan view similar to Figure 1 and illustrating the apparatus having a coil of tubing wound thereon;

Figure 5 is an enlarged fragmentary front elevational view showing an initial loop of tubing disposed thereon;

Figure 6 is a front elevational view similar to Figure 5 illustrating one position of the apparatus during the winding operation;

Figure 7 is a greatly enlarged sectional view taken along the plane VII—VII of Figure 5;

Figure 8 is a front elevational view illustrating the apparatus having a formed tubing coil thereon;

Figure 9 is a view similar to Figure 8 illustrating the expansion of the forming mandrels after winding has been completed;

Figure 10 is a view similar to Figures 8 and 9 showing contraction of the winding mandrel after the coil has been formed and immediately prior to removal of the coil therefrom;

Figure 11 is an elevational view of a helically wound coil of the present invention;

Figure 12 is a plan elevational view of a finished sinuous condenser tube made in accordance with the present invention; and

Figure 13 is an end view of the sinuous length of tubing of Figure 12.

As shown on the drawings:

In Figure 1, reference numeral 10 refers generally to an apparatus of the present invention including an upstanding support member 11 surmounted by a journal 12 rotatably supporting therein a shaft 13 extending axially therethrough.

The rear end of the shaft 13 has pinned thereto for rotation therewith a sprocket 14 receiving a driving sprocket chain 15 lapped about a driving sprocket 16 secured to the output shaft of a speed reducer 18 driven by a prime mover 17, such as an electric motor or the like.

The shaft 13 has secured thereto for rotation therewith a winder plate 20. As best seen in Figure 2, the winder plate 20 is generally rectangular in outline and has its geometrical center apertured to receive the shaft 13.

The shaft 13 carries thereon, immediately adjacent the winder plate, a bell crank 21 which, as best illustrated in Figure 3, is provided with a rearwardly projecting boss 22 rotatably disposed on shaft 13. The bell crank is provided with an arcuate upper surface 24 provided with spaced transverse grooves 25-27, inclusive. The boss 22 carries an upwardly extending arm 28 provided with a terminal flange 29 overlying the bell crank surface 24. The arm 28 carries directly beneath the flange 29 a vertically apertured guide block 30 slidably receiving a locking pin 31 having a lower end resiliently urged, as by compression spring 32, into a selected one of the slots 25-27, inclusive. A bell crank actuating arm 33 is secured to that edge of the bell crank opposite the edge 24 to provide means for rotating the bell crank about the shaft 13 upon lifting the locking pin 31 from the locking slots or recesses 25-27 of the bell crank.

The bell crank 21 carries oppositely directed link arms 34-35 pivoted to the bell crank, as by pivot pins 36. The arm 35 carries at the free end thereof a shaft bolt 37 passing through an arm aperture 38 and through an elongated slot 39 in the plate 20 (Figure 4). The shaft bolt 37 has its head recessed in a cylindrical winding mandrel 40 projecting beyond the front face of the plate 20. A nut 41 is threadedly retained on that end of the shaft bolt 37 projecting beyond the arm 35 to secure the arm 35, the shaft bolt 37, and the mandrel 40 into a movable unit.

The other arm 34 has its free end apertured as at 42 (Figure 7) to receive a shaft bolt 43. The shaft bolt 43 pivotally secures the arm 34 to a pair of links 44 and 45, each having registering apertures 46 therein receiving the bolt. The apertured end of the upper link 44 is recessed, as at 47, to accommodate the free end of the arm 34, while the lower link 45 is similarly recessed adjacent its apertured end, as at 48, to receive both the apertured ends of the link 44 and the arm 34. The links 44 and 45 have secured thereto additional winding mandrels 49 and 50, respectively, each mandrel projecting from the same surface of the plate 20 as the mandrel 40 hereinbefore described. Each of the mandrels 49 and 50 is secured to its link 44 and 45, respectively, by a partially recessed screw 51 threadedly retained by the links and extending through corresponding elongated slots 53 and 54, respectively, in the plate 20.

It will be seen that upon manipulation of the handle 33 in a clockwise direction, as seen in Figure 3, following removal of the locking pin 31 from the slot 26 against the action of the spring 32, the arms 34 and 35 will be actuated toward the remote ends of the plate 20, thereby spreading the winding mandrels 40, 49 and 50 from one another and from the center of the plate.

Conversely, upon actuation of the handle 33 in a counter-clockwise direction, the winding mandrels will be withdrawn toward one another. The position of the slot 25 in relation to the locking pin 31 indicates the furthest spreading movement of the mandrels, while the relation between the slot 27 to the locking pin 31 indicates the fully retracted position. Normally—that is, during actual winding operations—the pin 31 is seated in the intermediate or operating position slot 26.

Again referring to Figure 1 of the drawings, the shaft 13 carries, intermediate the bell crank 21 and the journal bearing 12, a sprocket 55 keyed thereto and receiving thereabout a sprocket chain 56 which is also lapped about a sprocket 57 keyed to a shaft 58 journaled within a bearing 59 carried by an upstanding support member 60 generally parallel to the support member 11 hereinbefore described for the shaft 13. Thus, the shafts 13 and 58 are geared together for rotation with the gearing ratio being determined, as is conventional, by the comparative sizes and numbers of teeth of the sprockets 55 and 57. In the illustrated form of the present invention, the shafts are driven in a one-to-one ratio.

That portion of the shaft 58 projecting beyond the bearing 59 is threaded, as at 61, the threads having a lead which is correlated with the remainder of the apparatus as will be hereinafter more fully described. The shaft 58 supports thereon a pressure bar 62 extending radially from the shaft toward the winder plate 20 and carrying on its undersurface a feeding guide 63 having a lower downwardly opening elongated slot 64 best illustrated in Figure 7. That end of the pressure bar 62 overlying the shaft 58 is provided with a lower feeding block 65 having an open bottomed arcuate topped slot 67 therein provided with an interior thread 68 in threaded engagement with the threaded portion 61 of the shaft 58.

It will be seen that, upon rotation of the shaft 58, the bar 62 and the feeding guide 63 will be advanced along the length of the shaft 58 which is parallel to shaft 13 upon which the plate 20 is disposed. The feeding guide 63 abuts one or more of the winding mandrels 37, 49 and 50 at all rotating positions of the plate 20. It is desirable to taper that end 69 of the feeding guide remote from the shaft 58 in order to insure smooth feeding of the tubing about the extreme mandrel 40, as will be hereinafter described, and also to insure smooth contact of this end of the feeding guide with the winding mandrels.

It will be noted, particularly in Figures 2 and 7 of the drawings, that the face of the plate 20 from which the winding mandrels 40, 49 and 50 project is provided with an elongated tapering groove 70 extending in a straight line from the undersurface of the winding mandrel 49 to the undersurface of the winding mandrel 40, the depth of the groove decreasing progressively from the mandrel 49 to the mandrel 40 and vanishing at the mandrel 40 for a purpose to be hereinafter more fully described. A clamping plate 71 is secured by a suitable means, as by a bolt or screw 72, to the same surface of the plate 20 to overlie a portion of the groove 70.

The operation of the apparatus hereinbefore described will be appreciated in Figures 4-10 of the drawings. To initially start the tube winding operation, a substantially straight tube length 80 is trained about a mandrel 40 with the free end 81 of the tube length being positioned with the groove 70 and the extreme free end of the tube underlying the mandrel 49 and projecting beyond the corresponding end surface of the winder plate 20. After the free end 81 of the tube length is positioned in the groove 70, the winder plate 20 is rotated from its initial position in the direction of the arrow shown in Figure 5. In the initial position, the mandrel 40 is at the right as viewed in Figure 5, mandrel 50 is in the upper left and mandrel 49 is in the lower left. From this initial position, rotation of the shaft 13 through 180° in the

direction of the arrow in Figure 5 bends the tubing about the mandrel 40 and into the shape shown in Figure 5.

That portion 81 of the tube 80 which is positioned within the groove 70 (Figure 7) is laterally displaced outside a vertical projection of the extreme ends of the pressure bar 62 and of the feeding guide 63, while that portion 83 of the tubing length 80 lapped about the mandrel 40 directly underlies the feeding groove 64 of the feeding guide 63. The reach of the tube 80 extending between the mandrels 40 and 49 and overlying the same is positioned within the groove 64, the pressure bar maintaining the feeding guide 63 in contact with the mandrels. Upon rotation of the plate 20 in a counter-clockwise direction, as indicated by the directional arrows of Figures 5 and 6, it will be seen that the pressure bar 62 and the feeding guide 63 ride about the periphery of the mandrel 49 until the position of Figure 6 is attained in which the feeding guide 63 contacts both the mandrels 49 and 50. Thus, the pressure bar smoothly deforms the tubing into surface contact with the mandrel 49, forming a smooth joining curve about a portion of the periphery thereof.

Upon further counter-clockwise rotation of the plate 20 about the shaft 13, the pressure bar 62 will be lowered with the feeding guide 63 maintaining contact with the mandrel 50 until the feeding guide contacts the mandrel 50 and the mandrel 40. Upon further rotation, the feed guide will contact the mandrel 40 until the position shown in Figure 5 is again realized, thus completing a single revolution of the plate 20.

It will be understood that the feeding guide 63 of the pressure bar 62 is advanced axially along the threaded portion 61 of the shaft 58 as this shaft is rotated in conjunction with the shaft 13 of the plate 20 by virtue of the hereinbefore described sprocket and chain feed arrangement. The axial advancement of the bar 62 of the feeding guide 63 upon one rotation of the shaft 58 is preferably equal to approximately the outside diameter of the tubing 80, so that a spirally wound relatively tight tubing coil is formed upon continued rotation, as illustrated in Figure 4. It will be appreciated that the slot 70, by laterally displacing the terminal portion 82 of the tubing 80 from its position underlying the pressure bar and feeding guide, will prevent interference of this portion of the tubing during the initial winding operation and before axial advancement of the bar and guide has been realized.

Counter-clockwise rotation of the plate 20 is continued until a desired length of tubing has been wound about the mandrel, or until a coil of the desired number of superimposed turns has been built up. In the manufacture of a ten-pass refrigerator condenser, for example, winding is continued while the plate 20 passes through four complete revolutions, at the conclusion of which the plate 20 is in the position illustrated in Figure 8 and the tubing 80 is severed, as at 84 in Figure 8. Alternately, the tubing may be cut to a predetermined length before winding is initiated, so that severance after winding is unnecessary. Of course, in order to sever the tubing, the bar 62 and the feeding guide 63 are removed from contact with the tubing 80, and while so removed, the terminal tubing portion 84 is deformed downwardly relative to the plate 20 to the position indicated in dotted outline in Figure 8. In this dotted position, the tubing terminal portion 84 extends from the mandrel 40 to overlie the mandrel 50, the tubing portion 84 thus overlapping or crossing the first free end 82 of the tubing 80 and each of the superimposed short runs 94 of the coils.

Inasmuch as the complete coil 86 of tubing has been formed, it is now desirable to expand this coil to insure a tight symmetrical formation of the coil about the mandrels. This stretching is accomplished by removal of the locking pin 31 from its position within the central slot 26, within which it has been positioned during the

coil forming operation, and the actuation of the lever 33 as hereinbefore described to bring the slot 25 into registry with the lower end of the locking pin 31. As hereinbefore described, this actuation of the lever moves the mandrels within their corresponding slots, thus stretching the coil from the center thereof to insure the formation of straight runs between the mandrels.

Next, to remove the coil 86 from its position about the mandrels, the mandrels are contracted by actuating the handle 33, after removal of the pin 31 from the position within the slot 25, so as to bring the slot 27 into registry with the locking pin. While the bell crank 21 is in this position, the pressure bar and guide are again elevated and the coil is simply removed from the retracted mandrel.

The coil which is thus formed comprises an irregular, preferably triangular, helix defined by straight tubing runs between curved tubing joining portions, the continuous coiled tubing length being spirally wound by virtue of the advancement of the feeding guide during rotation. As more particularly illustrated in Figure 11 of the drawings, the finished coil 86 comprises elongated straight runs 91 and 92 joined at one end by curved portion 93 and at the other end by a short run 94. The free ends 82 and 84 are joined to the terminal bend of the coil by the curved portions 93 thereof. The triangular helical coil thus formed is compact and small in overall size to facilitate handling and/or shipping during or prior to subsequent formation of the sinuous tubing length.

Upon opening or spreading the coil, the configuration of Figure 12 is obtained in which the runs 91 and 92 are parallel with the short runs 94, being aligned to form joining portions between the runs 91 and 92 of the same turn, and the curved portion 93 joining the runs 91 and 92 of adjacent overlapping turns of the helical coil as originally formed.

As shown in Figure 12, the end 82 overlaps the short straight run 94 of the initially formed turn, while the terminal end 84 underlies the short reach 94 of the last formed turn, the end portions 81 and 87 also being parallel to one another and to the runs 91 and 92 hereinbefore described.

It will be seen that the end product prepared by the use of the apparatus hereinbefore described is a sinuous length of tubing well adapted for attachment to a heat exchanger plate to form a plate-and-tube type heat exchanger, such as that described in my pending application for patent, Serial No. 81,970, filed March 17, 1949, now Patent No. 2,660,412 issued November 24, 1953, and assigned to the assignee of the instant invention.

The present application is a division of my co-pending application Serial No. 173,083, filed July 11, 1950.

It will be understood that modifications and variations may be effected without departing from the scope of the novel concepts of the present invention.

I claim as my invention:

1. In a winding apparatus, an elongated winder plate, a first mandrel carried at one end of said winder plate on one side thereof, second and third mandrels carried at the opposite end of said winder plate at said one side thereof to define with said first mandrel and said winder plate a generally triangular winding frame, said winder plate having a groove of increasing depth extending from one side of said first mandrel along said winder plate to a position between said second and third mandrels, and means for winding tubing or the like on said mandrels with one end of the tubing or the like extending in said groove and with the adjacent portion of the tubing or the like extending around the mandrels in close relation to said winder plate, the depth of said groove at the end thereof between said second and third mandrels being sufficient to accommodate the end of the tubing or the like in laterally displaced relation to succeeding turns of the tubing or the like on the mandrels.

2. In a winding apparatus, an elongated winder plate, a first mandrel carried at one end of said winder plate on one side thereof, second and third mandrels carried at the opposite end of said winder plate at said one side thereof to define with said first mandrel and said winder plate a generally triangular winding frame, said winder plate having means on said one side thereof for positioning an initial length of tubing or the like to extend from between said second and third mandrels and around said first mandrel, and means for winding tubing or the like on said mandrels with said initial length of tubing or the like positioned by said means and with the adjacent portion of the tubing or the like extending around the mandrels in close relation to said winder plate.
